**DYEING HAIR WITH 2,3,6-TRIAMINOPYRIDINE
AND SALTS THEREOF**

Stanley Brechner, West Orange, and Leonard A. Como, Franklin Boro, N.J., assignors to Warner-Lambert Pharmaceutical Company, Morris Plains, N.J., a corporation of Delaware

No Drawing. Filed Aug. 3, 1966, Ser. No. 569,851
8 Claims. (Cl. 167—88)

The present invention relates to a method employing novel compositions comprising 2,3,6-triaminopyridine or its salts for dyeing hair to impart a greenish-blue color thereto as well as to compositions combining said 2,3,6-triaminopyridine together with other dyes to give other shades.

It is known in the art that in order to produce bluish or greenish-blue shades when dyeing hair with amine dyes, one must employ at least two separate oxidizable amines. For example, aminobenzenes such as m-diaminobenzenes or derivatives thereof must be combined with other amines such as o- or p-diaminobenzenes and on oxidation with a suitable oxidizing agent such as hydrogen peroxide, urea peroxide, sodium borate and the like, the combination yields a blue color. 2,6-diaminopyridines or substituted 2,6-diaminopyridines must be combined with aminobenzenes to give a blue color on oxidation. For example, U.S. Patent No. 3,200,040 discloses that 2,6-diaminopyridine or substituted 2,6-diaminopyridines in combination with certain diaminobenzenes or aminophenols will produce a blue color on treatment with oxidizing agents. The 2,6-diaminopyridine alone produces only a pale yellow color. Accordingly, combination products were the only products available heretofore if it were desired to impart a blue shade to the hair employing oxidizable amines. We have now found that a greenish-blue color may be imparted to hair by oxidation employing but a single oxidizable amine. Accordingly, we provide novel compositions of matter containing but a single oxidizable amine which when treated with an oxidizing agent yields a greenish-blue dye which may be used to dye hair with a remarkable degree of consistency where the intensity of coloration imparted to hair is not only controllable but reproducible time after time.

In accordance with this invention, these novel and highly desirable results are attained by treating hair with a composition containing 2,3,6-triaminopyridine in amounts described below and in the presence of a suitable oxidizing agent. The intensity of coloration produced on hair is in direct proportion to and dependent upon the concentration of 2,3,6-triaminopyridine employed. Generally speaking, a satisfactory greenish-blue color may be obtained by applying to the hair a composition containing about 0.01% to 2.0% by weight of 2,3,6-triaminopyridine and then oxidizing the dye in said composition in situ.

The 2,3,6-triaminopyridine used in this composition is prepared by catalytically reducing 3-phenylazo-2,6-diaminopyridine in the presence of hydrochloric acid as described below in Example 1.

The 2,3,6-triaminopyridine may be employed in the form of its acid addition salts, such as 2,3,6-triaminopyridine dihydrochloride, 2,3,6-triaminopyridine sulfate and other suitable salts.

Such salts are readily prepared by the usual methods, such as, for example, the reaction of a stoichiometrically equivalent amount of the base and the desired acid in an inert common solvent. Examples of acids which are suitable for the preparation of acid addition salts of the amine base of this invention are inorganic acids, such as, for example, hydrochloric, nitric, sulfuric, phosphoric, and the like acids, and organic acids, such as, as for ex-

ample, benzoic, acetic, salicyclic, maleic, tartaric, citric and the like acids.

The 2,3,6-triaminopyridine in the form of its free base or in the form of its acid addition salts may then be dissolved in water and used as such or they may also be dissolved in a suitable vehicle for carrying hair dyes such as those described by Kass in American Perfumer and Aromatics, vol. 68, No. 1, pp. 25-28, July 1956. Examples of such vehicles are those that contain ammonium oleate, fatty acid esters, fatty alcohols, ethoxylated fatty alcohols, fatty amines, ethoxylated fatty amines, phosphate esters and the like. These vehicles may optionally contain wetting agents such as the condensation product of fatty acids containing 6 to 20 carbon atoms with diethanolamine or monoethanolamine, the condensation product of the methyl esters of fatty acids with diethanolamine or monoethanolamine. The term "fatty acids" used in the above description includes acids such as capric, lauric, myristic, palmitic, stearic, linoleic, oleic, ricinoleic, linolenic or mixtures of fatty acids occurring in natural fats and oils such as tallow, cocoanut oil, castor oil and the like.

The term "fatty alcohols" used in the above description includes alcohol such as lauryl alcohol, oleyl alcohol, myristyl alcohol, cetyl alcohol, stearyl alcohol, alcohols extracted from lanolin and the like, and mixtures thereof.

The active ingredient may be present in amounts of from about 0.01 to 2.0% by weight. The final solution may have a pH value of about 8 to 11 and this may be achieved by the addition of a base such as ammonium hydroxide.

For use the user combines the solution containing the active ingredient with about 1 to 2 parts by volume or by weight of a suitable oxidizing agent such as urea peroxide, hydrogen peroxide, sodium borate and the like. The choice of the oxidizing agent is not critical and other conventional oxidizing agents useful in hair bleaching may also be used. The amine oxidizing agent mixture is then applied to hair desired to be dyed. The solution is allowed to remain in contact with the hair for about 10 to 30 minutes. The hair is then shampooed and after drying is found to assume the new shade.

We have found that 2,3,6-triaminopyridine if desired may also be combined with other amines such as those disclosed in U.S. Patent No. 3,200,040 or diaminobenzenes or combinations thereof to give other hair coloring compositions.

For example, 0.01% to 2.0% by weight of 2,3,6-triaminopyridine may be combined with 0.01% to 2% by weight of o-, m- or p-diaminobenzenes or combinations of o-, m- or p-diaminobenzenes to give other colorations. Instead of using diaminobenzenes in these combinations we have found o-, m- or p-diaminopyridines may be used.

The following examples are included in order to further illustrate the invention.

Example 1.—Preparation of 2,3,6-triaminopyridine

A suspension of 124.5 g. (0.5 mole) of 3-phenylazo-2,6-diaminopyridine in 500 ml. of water and 200 ml. of 37% HCl is reduced in a Parr hydrogenator in the presence of 0.4 g. of 5% Pd on carbon catalyst. The reduction proceeds rapidly to completion at 20 to 30° C. The catalyst is filtered at once before the product can precipitate and the colorless filtrate is diluted with an equal volume of isopropanol. After standing in the cold for several hours the dihydrochloride precipitates as transparent colorless prisms and is filtered, washed with isopropanol and dried to constant weight in vacuo. The first crop weighs 41 g. and melts with decomposition starting about 230° C. A second crop can be obtained by concentration of the filtrate to give a total yield of about 70% of theory.

If necessary, the material can be further purified by dissolving in a small quantity of water and precipitating with excess HCl.

The compositions of the following Examples 2 to 7 are prepared by simple mixing procedures.

Example 2

Greenish-blue coloration:

2,3,6-triaminopyridine dihydrochloride ----- percent by weight 0.02
The condensation product of 10 moles of ethylene oxide and nonyl phenol ----- do 20.0
Sodium sulfite (as anti-oxidant) ----- do 0.25
Sufficient ammonia solution to yield a solution having a pH 9.
Distilled water to make ----- percent by volume 100.00

Example 3

Light warm brown coloration:

Ammonium oleate ----- percent by weight 20.00
p-phenylenediamine ----- do 0.25
2,3,6-triaminopyridine dihydrochloride ----- do 0.15
Anti-oxidant (sodium sulfite) ----- do 1.00
Ammonia (28%) to adjust the pH to 9.5.
Distilled water to make ----- percent by volume 100.00

Example 4

Dark ash brown coloration:

Lauric diethanolamine ----- percent by weight 3.00
Ammonium oleate ----- do 2.50
p-phenylenediamine ----- do 0.25
2,3,6-triaminopyridine dihydrochloride ----- do 0.25
Anti-oxidant (sodium sulfite) ----- do 1.00
Ammonia (28%) to pH 9.5.
Distilled water to make ----- percent by volume 100.00

Example 5

Dark blue-black coloration:

Cocoanut monoethanolamide ----- percent by weight 2.00
Propylene glycol ----- do 6.00
p-phenylenediamine ----- do 0.85
2,3,6-triaminopyridine dihydrochloride ----- do 1.10
Anti-oxidant ----- do 1.00
Ammonia (28%) to pH 9.5.
Distilled water to make ----- percent by volume 100.00

Example 6

Orange red coloration:

Triethanolamine lauryl sulfate ----- percent by weight 20.00
2,5-diaminopyridine dihydrochloride ----- do 0.50
2,3,6-triaminopyridine dihydrochloride ----- do 0.05
Anti-oxidant ----- do 0.25
Ammonia (28%) to pH 9.0.
Distilled water to make ----- percent by volume 100.00

Example 7

Light warm brown coloration:

Ammonium oleate ----- percent by weight 20.00
2,5-diaminopyridine dihydrochloride ----- do 0.45

2,3,6-triaminopyridine dihydrochloride ----- do 0.025
Anti-oxidant ----- do 0.25
Ammonia (28%) to pH 9.0.
Distilled water to make ----- percent by volume 100.00

Example 7A

Diester of phosphoric acid and oleic acid ----- percent by weight 5.00
Monoester of phosphoric acid and oleic acid ----- do 5.00
2,5-diaminopyridine dihydrochloride ----- do 0.40
2,3,6-triaminopyridine dihydrochloride monohydrate ----- do 0.06
Anti-oxidant ----- do 0.25
Ammonia (28%) to pH 9.0.
Distilled water to make ----- percent by volume 100.00

Example 8

Medium ash brown coloration:

The condensation product of 10 moles of ethylene oxide and nonyl phenol ----- percent by weight 20.00
2,5-diaminopyridine dihydrochloride ----- do 0.40
2,3,6-triaminopyridine dihydrochloride ----- do 0.05
Anti-oxidant ----- do 0.25
Ammonia (28%) to pH 9.0.
Distilled water to make ----- percent by volume 100.00

Example 9

In order to use these compositions to impart the desired shade to human hair one part of the selected composition is mixed with approximately 1 to 2 parts of 6% hydrogen peroxide solution.

The resulting solution is then applied to white hair and allowed to remain in contact with the treated hair for about half an hour after which the hair is rinsed and shampooed. After drying the hair assumes the shade as described.

It is understood that the foregoing detailed description is given merely by way of illustration and that many variations may be made therein without departing from the spirit of our invention.

We claim:

1. Process for imparting a greenish-blue coloration to hair which comprises contacting hair with an aqueous solution of about 0.01% to 2% by weight of 2,3,6-triaminopyridine or the salts of 2,3,6-triaminopyridine in the presence of an oxidizing agent.

2. Process for imparting a greenish-blue coloration to hair which comprises contacting said hair with an aqueous solution containing about 0.01% to 2% by weight of 2,3,6-triaminopyridine or the salts of 2,3,6-triaminopyridine in the presence of a hydrogen peroxide solution.

3. A composition for dyeing hair which comprises as active ingredient of about 0.01% to 2% by weight of 2,3,6-triaminopyridine or the salts of 2,3,6-triaminopyridine in an aqueous solvent.

4. A composition for dyeing hair which comprises as active ingredient of about 0.01% to 2% by weight of 2,3,6-triaminopyridine or the salts of 2,3,6-triaminopyridine and about 0.01% to 2% by weight of 2,6-diaminopyridine.

5. A composition for dyeing hair which comprises as active ingredients about 0.01 to 2.0% by weight of 2,3,6-triaminopyridine and 0.01% to 2.0% of o-, m-, or p-diaminobenzenes or combinations thereof.

6. A method for dyeing hair which comprises contacting hair with a composition in accordance with claim 5 in the presence of an oxidizing agent.

7. A method in accordance with claim 6 wherein said oxidizing agent is hydrogen peroxide, urea peroxide or sodium perborate.

8. A composition for dyeing hair which comprises as active ingredients of about 0.01 to 2.0% by weight of 2,3,6-triaminopyridine and 0.01% to 2.0% of o-, m-, or p-diaminopyridines.
